UNITED STATES PATENT OFFICE.

JOHN KAEFER, OF HAMILTON, OHIO.

DECORATOR'S APPLIANCE.

1,189,121.

Specification of Letters Patent. Patented June 27, 1916.

Application filed May 6, 1914. Serial No. 836,686.

To all whom it may concern:

Be it known that I, JOHN KAEFER, a citizen of the United States, residing at Hamilton, in the county of Butler and State of Ohio, have invented new and useful Improvements in Decorators' Appliances, of which the following is a specification.

The invention has for its principal object the increase of facility in manipulation and 10 adjustment of pottery and other articles in course of decoration or other treatment.

A particular aim is to give an improved means for engaging and securing an object in a coaxial position on the supporting plate 15 which in the present instance comprises the usual disk, modified but applicable to use in the familiar ways heretofore practised.

It is also an aim to give a ready means for adjusting the device to hold objects of 20 widely various shapes.

A further aim is to present means for accurately spacing decorative details on an object without the necessity for making measurements.

25 It is a purpose to provide an arm rest of an improved form.

A valuable attainment of the invention is the provision of means to hold a stencil or stencils of various kinds which will also 30 serve as a straight-edge and will be co-operative with the arm rest.

Additional objects advantages and features of invention will appear, some of which will be apparent in the construction, 35 arrangement and combination of parts hereinafter described and shown in the drawings, where—

Figure 1 is a perspective view of the device in use, Fig. 2 is a bottom view of the 40 table disk, Fig. 3 is a detail view of the arm rest, Fig. 4 is a vertical sectional view of the mounting of the disk, Fig. 5 is a detail of the spacing device. Fig. 6 is a detail view of the straight edge and mounting.

45 There is illustrated a cast base frame 10, including the circular portion 11, having the concentric vertical shaft 12 fixed thereon, the upper end of which is conically finished for a reason which will appear. The shaft 50 is circumferentially grooved as at 14 at a short distance from its lower end. Surrounding the shaft there is an anchor plate 15 also fixed to the base. This and the attachment of the shaft may be accomplished 55 as shown by forming a tenon 12' on the

lower end of the shaft threaded at its outer part, and inserted through a suitable opening in the plate and the base,—on the lower side of the base a boss 16 being formed—and engaging a nut 17 on the lower end of 60 the tenon. The anchor plate is provided with any desired number of concentric series of apertures 18—in this case, three series—each having a different number of openings and different intervals between 65 the radii intersecting the apertures.

Engaged revolubly on the shaft there is a shaft 19, closed at its upper end and suitably formed thereat for ready rotation while supported on the conical portion of 70 the shaft 12. A set screw 20 is engaged through a collar 21 fixed or formed on the lower end of the shaft 19 the screw projecting through the shaft also, at a height to engage in the groove 14, whereby the device is retained revolubly on the shaft. The collar 21 is provided with an extension 22 having vertical bores 23 therethrough arranged to register with respective series of 75 apertures 18. Engageable slidably therein there is a sleeve 24 Fig. 5, having a transverse notch 25 in one side, and a shoulder 26 limiting its downward movement in the bores 23. A pin 26' is engaged revolubly 80 in the extension 22, intersecting all the bores 23, and being cut away on one side whereby when turned to one position the bores 23 will be cleared, while in the other position, the pin will project across the bores, thus being adapted to engage in the 85 notch 25 of the sleeve and hold it against removal from whatever bore it may be inserted. The sleeve has a spring-pressed locking pin 27 slidable therein and normally projecting through the lower end of the 90 sleeve for engagement in the apertures 18, the pins 26 and 27 are each headed for convenient manipulation. Engaged revolubly on the shaft 19 there is a hub 28 in the form of a cylinder having a flange 29 at its upper end, its lower end being seated against the collar 21. A set screw 30 is provided by which the hub and shaft may be locked together. Attached to the flange and supported thereover in a plane at right angles 95 to the axis of the hub there is a table disk 31, radial ribs 32 being formed on its under side resting upon the flange 29, whereby the under side of the disk proper is set slightly 100 above the hub. The sleeve 24 carries a spur 105 110

gear 32' just over the flange, meshed with gear sectors 33 pivoted on the under side of the disk 31 between the ribs 32. There are shown three of these sectors, and a corresponding number of arcuate slots 34 concentric to the pivots of respective sectors, the outer ends of the slots being closely adjacent the periphery of the disk, and their inner ends being close to the gear 32'. At 10 what may be termed their outer sides the sectors are provided with threaded apertures 35 alined with the respective slots in which apertures there are engaged in a suitable manner long screws 36 extending 15 upwardly through the slots and having heads 37 on their upper ends adapted to engage objects to be decorated when moved inwardly thereagainst. The screws may project as far as desired below the disk, and 20 will at all times be free for movement with the sectors. The heads of the screws may be padded or otherwise formed, and will serve to be grasped for manipulation, as well as to engage the article to be held.

25 It will be apparent from the foregoing that any article of symmetrical form may be accurately centered with great ease by simply setting it within the screws, upon the disk, the screws having been rotated 30 properly to dispose their heads at the proper height to firmly engage the article, and simply turning the disk while the spring pressed pin 27 is engaged with one of the apertures 18, the set screw 30 having been 35 loosened. As the disk is turned in the proper direction, the relative change of position of the gear 32' will cause movement of the sectors, carrying the screws against the article to be held, after which the screw 40 30 is tightened to hold the object so engaged. The reverse operation will release an object after decoration.

At the opposite end of the base 10 from the portion 11 there is an upstanding hollow arm 40, rectangular in cross section, a slot 41 being formed in its outer side communicating with the interior of the arm. Snugly and slidably held in this arm there is a stem member 42 also of rectangular 50 form, carrying at its lower part a binding screw 43 projected through the slot 41 and having an operating head therewithout. An H-shaped cross head 44 is carried at the upper end of this stem through the apertured 55 ends of the arms of which there are slidable two rods 45, thereby maintained in a common horizontal plane, and supported upon these by suitable brackets 46 there is an arm rest 47, consisting of a plain board for the most part. A binding screw 48 is engaged 60 in the head 44 so as to impinge on the board when the rest has been adjusted longitudinally to the desired position.

In the upper side of the arm rest two 65 threaded sockets are provided in which

screws 49 may be engaged to hold a straight-edge 50 in place. This straight-edge consists of two parts hingedly connected, the outer receiving the screws 49 therethrough whereby it may be held with the joint just beyond the inner edge of the rest for vertical oscillation of the projected part, whereby it may be adjusted above or below the rest at any desired inclination. The hinge joint may be provided with any desired frictional 70 device to prevent the swinging portion from having too free a movement. Stencils are also provided, having shanks or holders 51, constructed to slip on the outer end of the swinging piece of the straight edge to hold the stencil convenient to the hand of the operator. The base 10 is narrow for the most part, the circular portion 11 being somewhat broader, and lateral stabilizing extensions 52 are formed at each side at its 75 central part.

In constructing a machine my present practice is to form the shaft 19 as a cylinder, carrying in the upper end the stub 53, by means of the pin 54, the stub projecting 90 sufficiently above the cylinder to allow proper securement of the gear 32' thereon. The extension 22 may also be formed separately if desired, although not so shown, being secured in any desirable manner to the 95 lower end of the shaft 19.

What is claimed:

1. A device of the character described comprising a base member, a rotatable work carrier thereon, a guide member spaced 100 from the carrier, an arm rest having a supporting portion slidably engaged with the guide, means for securing the stem adjustably therein said arm rest being movable toward and away from the carrier.

2. A device of the class described comprising a base, a rotatable work carrier thereon, a guide element on the base spaced from said carrier, an arm rest slidably mounted thereon, means for holding the arm rest in adjusted position, and an oscillatable device carried by the arm rest adjacent said carrier, constructed, arranged and adapted for movement for disposition in various relations to the work carrier.

3. In a machine of the class described, a rotatable work carrier, a plurality of gear sectors pivoted thereon, the pivots of the gears being concentrically spaced around the axis of rotation of said work carrier, work engaging members carried at the outer sides of the sectors, a concentric revoluble gear coaxial with the said work carrier and meshed with all of the sectors, means carrying said gear revolubly, a supporting device for the rotating member and said last-named means, means to fix the gear with relation to the supporting device, at times, means to fix the gear with relation to the work carrier at times, and work engaging devices 130

carried by the outer side of said sectors and projecting from said work carrier for the purposes described.

4. In a decorator's work holder, a base, two concentric revoluble and relatively revoluble members thereon, one being a work support constructed to support work centrally thereof as a table, movable work securing devices constructed to engage by inward movement work carried by the support, and operative connections between the securing devices, and the other of the said relatively revoluble members operative to draw the securing devices into engagement with work by relative movement of the said revoluble members.

5. A device for rotatably supporting work comprising a broadened base, a plurality of concentric series of apertures being formed therein, a concentric stub shaft thereon, a hollow shaft revoluble on the stub shaft, a work carrying disk on the upper end of the hollow shaft, a movable member carried by the hollow shaft constructed for selective engagement in said apertures, means on the disk to clamp work, and operative connections between the last named means and the base for inward and outward movement of the clamping means by relative movement of the disk and base.

6. A work holder comprising a base including an anchor portion having a plurality of concentric series of apertures, a concentric stub shaft within the series of apertures, a hollow shaft revoluble thereon, a laterally adjustable spring pressed pin carried by the last named shaft for engagement selectively with said apertures, a hub member revoluble on the last named shaft, a gear on the last named shaft adjacent the upper end of the hub, a work carrier carried by the hub, a plurality of gear sectors pivoted thereon in mesh with said gear, work engaging members projected outwardly of said carrier carried by the sectors, and means for fixing the hub upon the sleeve at times.

7. In a work holder of the class described, a base, a disk mounted revolubly thereon, a very small gear concentric therewith, means supporting said gear revolubly with respect to said base and said disk, a plurality of arcuate slots being formed in the disk in the form of segments of circles without the

gear, the slots having inner ends registering with the gear teeth and outer ends close to the edge of the disk, gear segments pivoted on the disk concentric with respective slots, work engaging members carried by the segments projecting slidably through the slots, adjustable means to connect the gear fixedly to the base, and means to connect the gear and disk fixedly with respect to each other at times.

8. A work holder comprising a base, a rotatable work carrier thereon, an anchor portion on the base, a multiplicity of series of openings arranged concentrically with the axis of rotation of the work carrier, a member movable with the work carrier including a portion disposed over the series of apertures, and having openings alined with respective series, a sleeve selectively engageable in said openings, means to secure it releasably therein, and a spring pressed pin therein tending to engage in the apertures when in operative position.

9. In a work holder of the class described, a base, a revoluble work carrier supported thereon, a hollow arm on the base parallel to the axis of the rotation of the carrier, an arm rest having a longitudinally adjustable stem thereon, said stem being slidably engaged in said arm, and means to secure the stem adjustably in the arm.

10. In a work holder of the class described, a base, a movable work carrier thereon, a hollow arm on the base, an arm rest supported thereon, a slideable stem thereon at right angles to the rest, said stem being engaged slidably in the arm, means to secure the stem adjustably in the arm, and an oscillable member carried by the rest movable toward and away from work in the carrier.

11. In a machine of the class described, a support, a movable work carrier thereon, a rest adjustable with respect thereto, an oscillable member carried by the rest adjacent said carrier and a stencil device adjustable on the oscillable member.

In testimony whereof I have hereunto set my hand in presence of two subscribing witnesses.

JOHN KAEFER.
